ABSTRACT

Swim/sporting event timer/counter. A waterproof housing has upwardly projecting digital displays and two spaced ultrasonic receivers. A swimmer wears an ultrasonic transmitter tuned to ultrasonic receivers. By measuring the time differential for the ultrasonic signals from the transmitter to reach the receivers in the housing, the position of the swimmer (i.e., in front of, directly over, or behind the housing), is determined. Laps are identified by determining when the transmitted signal changes from being received by the two receivers by an increasing time differential to being received by a decreasing time differential. Each time the swimmer passes over the housing, the numbers on the display are inverted so that the swimmer may look down into the water and see the time regardless of which direction the swimmer is traveling in the lane or other predetermined course.

TIMING AND LAP COUNTING DEVICE FOR A SWIMMER

FIELD OF THE INVENTION

The present invention relates to sporting event lap counters/timers and, in particular, to sporting event lap counters/timers used by swimmers.

BACKGROUND OF THE INVENTION

It is important for competitive swimmers or other persons travelling laps on predetermined courses to know the time it takes to complete each lap, as well as other statistics such as the total elapsed time, lap number and temperature. Several devices are known in the art for providing some of these statistics.

Two of the most common devices used by swimmers are (1) water-resistant wrist-watches that are self-activated and (2) large electrical clocks that are above the water and are visible to swimmers. The clocks are more generally used in recreational lap swimming and are usually located at the end of a swimming lane. They require a swimmer to raise the swimmer's head above the water level to view the last split time swam by the swimmer, and the time depicted is an approximate time because the clock does not reset at the end of each lap swam. The wrist-watches are not workable for swimmers except for monitoring total elapsed time, because a swimmer must activate the watch after each lap to monitor split times, thereby interrupting swimming activity. As a result, it is very difficult to conveniently view progress during the swim.

One prior lap timer, disclosed in Dawley, U.S. Pat. No. 4,518,266 shows a lap timer having a kick pad which is submerged in water, and readouts that are positioned above the water level. Each time a swimmer completes a lap, the swimmer makes active contact with the kick pad and a lap time is computed. This device has the deficiencies of (a) requiring the swimmer to specifically attempt to touch the kick pad during each lap, and (b) requiring the swimmer to lift the swimmer's head out of the water to view the readouts. As a result, it is very difficult for the swimmer to view progress during the swim.

Other electronic devices for use by swimmers and divers are known. For example, Charbonnier, U.S. Pat. No. 3,696,610 discloses an underwater wristwatch containing a timer to indicate the duration of a compression stage to be observed by a diver. However, this patent does not disclose a device for determining elapsed time or the number of laps traversed by a swimmer, nor does it include any digital displays. Siegal, U.S. Pat. No. 4,700,369 and Kasoff, U.S. Pat. No. 4,932,045 also disclose swim lap counters in which the completion of a lap is indicated by a physical switch. The Siegal device, like Dawley, requires that a switch be manually depressed by a swimmer upon completion of each lap. Both of these devices have the shortcoming of requiring the swimmer to consciously locate and depress the switch upon completion of each lap. Kasoff discloses a lap counter that may be worn in the palm of a hand or the bottom of a foot as shown in its FIGS. 4 and 5, and is actuated by the swimmer striking the device against the side of pool. Although Kasoff does not require that the swimmer contact any particular portion of the pool upon completion of a lap, the swimmer must still consciously contact the side of the pool with sufficient force to actuate the mechanical switch. The Siegal and

Kasoff devices include underwater digital displays of lap counts, while the Dawley device includes displays for additional information including split time and elapsed time. However, none of these devices is configured so it may be placed on the bottom of a pool.

Malone, U.S. Pat. No. 4,780,085 discloses a lap timing device that does not detect completion of a lap by a mechanical switch, but rather by an ultrasonic proximity detector positioned at the end of a swimming lane. An ultrasonic wave is normally absorbed by water indicating a swimmer is not positioned in proximity to the timer. However, when the swimmer approaches the counter, ultrasonic waves are reflected back toward the counter to generate a lap completion signal. The device also displays a variety of statistics regarding a training session, including total swim time, average lap time, and minimum and maximum lap times. However, the readouts of the Malone device are not observable by a swimmer looking toward the bottom of a pool, nor they observable by a swimmer regardless of the direction in the pool lane the swimmer is swimming. Moreover, the proximity detection system does not provide sufficiently accurate results.

Crews, U.S. Pat. No. 4,857,886 discloses a networked racing vehicle timing/location system in which multiple transceivers are positioned at various stages along a race course and also on each race vehicle. Each stationary transceiver transmits a narrow width signal. When the transceiver on a vehicle detects a narrow width signal from a stationary transceiver, the vehicle transceiver transmits a coded signal to the stationary transceiver which identifies the particular vehicle. A remote computer is connected to all stationary transceivers in order to continuously monitor the location of all vehicles. However, in this system, the vehicles must have receivers, and times are not computed by comparing the time it takes for a single transmitted signal to reach two spaced receivers.

Asai, U.S. Pat. No. 4,681,118, discloses a system in which a swimmer may wear a heart monitoring device that transmits signals to generate an electrocardiogram of the swimmer. However, this system does not generate total or split lap times, and multiple swimmers in the same pool using such devices would generate interfering signals.

Finally, none of the above-reference patents discloses a swimming lap counter/timer that includes a means for storing data regarding swimming sessions and transferring the data to a computer for subsequent analysis.

One object of the invention is to provide a swimmer timer that is waterproof and fully submersible, and which includes an upwardly projecting display so that it may be viewed by a swimmer without the swimmer raising the swimmer's head out of the water.

Another object of the invention is to provide a swimmer timer that does not require a swimmer to make a physical contact with a switch to indicate completion of a lap.

Another object of the invention is to provide a swimmer counter capable of inverting the statistical display so that the display is readable by the swimmer when moving in either direction.

Another object of this invention is to provide an easily transportable swim timing device for use in any swimming facility and to facilitate personal use as an individual training timing device.

Another object of the invention is to provide an timer/counter that can be totally immersed in water and which has a reduced risk of electrical shock.

Another object of the invention is to provide a method for processing signals from an athlete and for automatically correcting lap split times based upon analysis of those signals.

BRIEF DESCRIPTION OF THE DRAWINGS

FIG. 1 is a perspective view of one embodiment of a counter/timer of the invention.

FIG. 2 is a top view of a belt containing an ultrasonic transmitter in accordance with the invention.

FIG. 3 is a top view of the counter/timer of the invention showing the statistical displays in non-inverted format.

FIG. 4 is a top view of the counter timer of the invention showing the statistical displays in inverted format.

FIG. 5 is a diagrammatic view showing how the invention may be placed in a swim lane and those points along multiple laps when readings are taken to provide the automatic timing correction capability of the invention.

FIG. 6 is a block diagram of electronic circuitry that may be employed in one embodiment of the invention.

FIG. 7 is a block diagram of a microcontroller based counter/timer in accordance with the present invention.

FIGS. 7a-7h are sub-block diagrams of the microcontroller based counter timer shown in FIG. 7.

FIG. 8 is a software flow diagram of software that may be used in connection with the circuit shown in FIGS. 6 and 7.

The appendix shows source code written in the PL/M language that may be complied and loaded in the memory shown in FIG. 6 to operate the hardware disclosed herein.

SUMMARY OF THE INVENTION

One embodiment of the present invention comprises a waterproof housing with three upwardly projecting digital displays readouts and two spaced ultrasonic receivers or sensors. A swimmer wears an ultrasonic transmitter tuned to the specific frequency of the ultrasonic receivers in the housing. The housing is placed on the bottom of a pool within about ten feet of the end of the starting wall of the swimming lane. By measuring the time differential for the ultrasonic signals from the transmitter to reach the two receivers in the housing, the position of the swimmer (i.e., in front of, directly over, or behind the housing), is determined. The timer begins when the diver first enters the water. The display shows the total time and the elapsed time for a specific lap. In one embodiment, completion of a lap is identified by determining when the transmitted signal changes from being received by the two receivers by an increasing time differential to being received by a decreasing time differential, although a single receiver employing the doppler effect may also be used. Each time the swimmer passes over the housing, the numbers on the display are oriented so that the swimmer may look down into the water and easily view the time regardless of which direction the swimmer is traveling in the lane or other predetermined course.

DETAILED DESCRIPTION

As shown in FIG. 1, one embodiment of the invention comprises a translucent, submersible housing 11

that includes a waterproof lid 12 sealed by a gasket (not shown). Housing 11 contains an internal power source such as a rechargeable six volt lead acid battery 13 and electronic components 14. On the top of lid 12 are positioned three upwardly projecting seven segment LCD displays 15, 16 and 17 and first and second receivers 18 and 19. Also mounted near the top of lid 12 are water temperature sensor 43 and first, second and third magnetic reed switches 30, 31 and 32, which may be actuated by a magnet passed in proximity thereto.

In the preferred embodiment, the device is used by a swimmer wearing a battery powered ultrasonic transmitter 24. As shown in FIG. 2, transmitter 24 may be attached to a transmitter housing 21 which may be secured to the swimmer by strap 22 and buckle 23. Transmitter 24 is tuned to the same frequency as receivers 18 and 19, preferably transmits in the frequency range of 20 KHz to 455 KHz, and emits a 4 millisecond pulse every 40 milliseconds. The transmitter is preferably activated by a MOSFET transistor having a gate forward-biased by two terminals exposed to the exterior of the housing so as to be automatically turned on by the change of conductivity when the water is entered, as shown in FIG. 7h.

To use the device, the swimmer then places counter housing 11 underwater approximately ten feet from the starting end of the pool lane, as shown in FIG. 5, and activates the device by passing a magnet in proximity to on/off magnetic reed switch 32. The swimmer should stand on the side of the device closest to the starting wall. The device has five operating modes: swim-session, display-data, serial-out, clear-sessions and display temperature. When the device is first turned on, it automatically enters the Swim-session mode. In this mode, the device will sense the pulsing signals from the transmitter worn by the swimmer to determine the direction of the swimmer, and hence, the starting wall. The device will display a series of four dashes in the visual display closest to the swimmer to indicate on which side of the device the starting wall is located. As described below, the swimmer may enter one of the other five modes by actuating the mode select switch as described below. However, assuming another mode is not selected, after about four seconds the top display will display "S-nn" where nn is the current session number about to begin (multiple sets of swim sessions may be stored in the device as described below), the middle display will show a count of 10 and start counting down to 0, and the bottom display (the display closest to the start end) will show all dashes.

If the swimmer wishes to enter a different mode, this may be accomplished by actuating mode select switch 31 until the desired mode is reached. These other modes are indicated by displaying in the middle visual display by the abbreviations SEE (display data mode), PC (serial out mode), CL (Clear-sessions mode), F (display temperature mode), and SESS (swim-session mode, if the swimmer re-enters this mode). Once the desired mode is reached, that mode may be entered by actuating the first magnetic switch 30. For all modes except the display data mode, the user may switch to a different mode by actuating the mode select magnet switch 32 again. To get out of the display data mode, the user must turn off the device by actuating the on-off switch 32, and then turn the device back on by actuating that switch again. Each mode is described in further detail below.

Swim Session Mode: When the swim session mode is selected as noted above, a 10 second countdown begins, which is shown in one of the visual displays in non-inverted format. This period gives the swimmer sufficient time to get out of the pool and prepare to dive in from starting end 33 of the pool lane. Sometime after the ten second period has elapsed, the swimmer dives into the water. Upon entering the water, which will occur at some point between A and B (in FIG. 5) for a jump start, receivers 18 and 19 will detect the signal from transmitter 24, and will start both a time counter and a lap counter. Alternatively, the time counter and lap counter will be started when the device detects forward motion toward the timer. The lap counter will start at 1 and will be displayed in second display 16. In the preferred embodiment, the time counter will start with a count of between 0.4 and 1.4 seconds, and preferably 0.9 seconds, to account for the approximate time that elapses between the time the swimmer begins to dive into the water and the time the transmitted signal is first received by the device. Two types of times will be displayed in the visual displays. The lap time will initially be shown in third display 17, and the total elapsed time will be shown in first visual display 15, as shown in FIG. 4.

Statistics regarding the swim session are initially displayed in non-inverted format by visual displays 15, 16 and 17 as shown in FIG. 4. Thus, the statistics are readable by the swimmer when the swimmer swims toward the opposite end 34 of the pool lane and looks toward the bottom of the pool. When the swimmer first enters the pool, the signals transmitted by transmitter 24 will reach first receiver 18 before it reaches second receiver 19. As the swimmer swims closer to the device, the time differential between the time the signal reaches the receivers 18 and 19 will decrease. When the swimmer passes over the device, the signal will reach receivers 18 and 19 substantially simultaneously. Approximately 4 seconds after the swimmer passes over the device, the device will invert the statistical displays as shown in FIG. 3. Thus, the displays will be easily readable by the swimmer during the subsequent return portion of the lap. When the displays are inverted, the lap time will be shown in display 15 instead of 17, and the total elapsed time will be shown in display 17 instead of 15. Thus, the lap time will always be the top number, the lap count the middle number and the total time the bottom number.

As the swimmer continues to swim towards opposite wall 34, the signal will reach second receiver 19 before it reaches first receiver 18. This time differential will continue to increase until the swimmer is either out of range of receivers 18 and 19, or until the swimmer reaches opposite end 34 and reverses direction. Thus, when this time differential changes from an increasing amount to a decreasing amount, completion of a half-lap can be detected.

The time differential between receipt of the signal by the receivers will continue to decrease until the swimmer is directly over the device as represented by point B of FIG. 5. At this time, the device will store in memory a reference time constituting the elapsed time at point B. The signal will thereafter be first received by first receiver 18, then by second receiver 19. When the swimmer reaches starting wall 33 and reverse direction as shown at point C, the time differential between receipt of the signal will again change from increasing to decreasing. This is how the preferred embodiment of

the device ordinarily detects completion of a lap. At this point, the lap counter shown in second display 16 will be incremented to show that the swimmer is on the next lap, and the lap time display will be frozen and stored as a third reference count. In addition, the displays will again be inverted so that they may be easily read by the swimmer the next time the swimmer passes over the device. When this occurs as shown by point D in FIG. 5, a fourth reference count is stored. In addition, a lap time verification routine is executed. This routine is executed because the third reference time C can sometimes be suspect due to noise in the signals received by receivers 18 and 19. In this routine, the difference between reference times B and D is computed. One half of this amount is taken and added to reference time B. This total, which is herein referred to as C' will exactly match reference time C if the swimmer took the same amount of time to swim from point B to C as was taken to swim from point C to D. However, this is rarely the case. A time window is computed which consists of the value of C', plus or minus a predetermined percentage of the difference between reference points B and D. In the preferred embodiment, this percentage is twenty five percent and is represented by range E in FIG. 5. If reference time C is within this time window, then it is assumed to be correct. If it is not within this window, then time reference C is replaced by time reference C', and the new value is displayed in the updated lap time visual display. The final lap time is also used to compute the lap time for the following time, and the above procedures are repeated for subsequent laps. Each time a lap is completed, the lap time is stored in computer memory.

In the preferred embodiment, the device detects completion of a swim session when it determines that the swimmer has failed to pass back over the device (point D in FIG. 5). Thus the time used to determine the end of the final lap is when the time differential between receipt of the signal by the receivers either begins to remain constant, begins to decrease, or when the signals are no longer received for a predetermined amount of time, indicating that the swimmer has either exited the pool or turned off the transmitter.

After detecting the end of the swim session, the device stops the time counter and displays the total elapsed time, water temperature (in the display previously used to show the lap number), and the last lap elapsed time. The swimmer can then place the device in any of the other four modes described by actuating mode select switch 31.

Display-Data Mode: The Display-Data mode allows the user to view the previously stored data. The user can scan sessions containing lap split times, total elapsed times, and water temperatures. There is a fast and slow scan rate that the user can select. Magnetic switches 30 and 31 serve as scan switches, with switch 31 causing a scan up for a session and switch 30 causing a scan down. Activation of either switch causes the scan rate to be slow initially. However, after approximately two seconds if the switch is still being activated the scan is increased to the fast rate.

Serial-Out Mode: The Serial-Out mode is used to transmit the previously stored data through an interface port, which is comprised of TXD transmit terminal 40, ground terminal 41 and RXD receiver terminal 42, to a user's personal computer by way of an asynchronous RS 232 serial interface. The transmission commences when a serial byte is received from the personal com-

puter and the transmission terminates when all session data has been transmitted.

Clear-Sessions Mode: The Clear-Sessions mode clears all session data while displaying which sessions are being cleared.

Display-Temperature Mode: The Display-Temperature mode converts the frequency produced by the resistance of a thermistor to a frequency converter circuit into a number that represents the water temperature in degrees Fahrenheit or degrees Celsius. The temperature is displayed on the lap display with a degree sign to the right of the units position.

A complete circuit diagram for one embodiment of the present invention is shown in FIGS. 6, 7, and 7a-7h, and in the appendix. Referring to FIG. 6, the main elements of the device are shown and consist of microcontroller minimum system 51, power control circuit 52, RS-232 interface 53, visual display module 54, temperature module 55, first and second ultrasonic receiver modules 56 and 57, address and control bus 58, and non-volatile RAM module 59. As shown in FIG. 7, the microcontroller minimum system comprises an 80C31 microprocessor 61, an 8282C integrated circuit 62 and a 27C64 integrated circuit 63. Each non-volatile RAM module is comprised of a HM6264LP 8K CMOS RAM from RCA and Dallas Semiconductor lithium battery powered smart socket, as shown in FIG. 7a.

Referring to FIG. 7b, the temperature module comprises frequency meter comprised of thermistor RT1, and 0.001 uF timing capacitor C1 coupled to schmidt trigger CMOS digital gates U1A-U1F located on a 4584 integrated circuit chip. FIGS. 7c, 7d and 7e show the three digital display modules. Each liquid crystal display comprises a four digit, seven segment FE202 display driven by a HC0438 driver. Inversion of the displays is accomplished by the software described in the appendix. The ultrasonic receiver circuits are shown in FIGS. 7f and 7g, and each comprises a National Semiconductor LM1812 ultrasonic transducer chip U1 connected to a 40 KHz transducer T1 and tuned by 15.8 mHz adjustable coil L1 and 1 nF capacitor C1. When a pulse of ultrasound is incident on receiving transducer T1, and electrical signal is produced. This electrical signal is amplified and integrated before it is routed to a threshold sensitive detector. The active low output of each detector is connected to one of the two external interrupts of the microcomputer. The transducer that is closest to the source of the emitted ultrasound initiates an interrupt to the microcomputer when the ultrasound is detected. The transducer furthest from the transmitter initiates an interrupt to the microcomputer some time later (sound propagation time differential between receiver). The microcomputer times the interval between the interrupts and identifies which receiver is closest to the ultrasound source.

FIG. 7h shows the transmitter circuit for the transmitter shown in FIG. 2. The battery powered belt-mounted pulsing signal transmitter is comprised of oscillators, an output driver, some logic, a charging circuit, a water-activated conductivity switch, and a transducer (transmitter). The oscillator used for the transmitted frequency is keyed on and off to produce a repetitive burst of transmitted ultrasound. The frequency of the transmitted signal can range from 20 KHz to 455

KHz depending upon the particular unit. The repetition rate of the transmitted signal can range from 10 HZ to 100 HZ and the duty cycle can range from 5-60% also being particular to the unit.

The system further includes the software shown in the Appendix. A flowchart for the basic software appears in FIG. 8. This software handles the microprocessor interrupts and compares the time differential between received pulsed signals. The software also includes logical timers and counters for tracking total times, lap times and lap counts, and updates each elapsed lap time count upon completion of a lap based upon the time differential between the times the pulsing signal reaches the first and second receivers. In the preferred embodiment of the software, counters are updated when the time differential between receipt of the pulses by the two receivers change from increasing to decreasing and the swimmer is at the start end. However, the software could be easily modified to update the counter means based on the being substantially no time difference between the time the pulsing signal reaches the first and second receivers, i.e. when a person is directly adjacent to or over the sensor, or based on a change in which receiver receives the signal first. The software also selectively displays the statistics on the visual display in either inverted or non-inverted format.

It will be appreciated to those of skill in the art that numerous changes could be made to the described embodiment of the invention without departing from the spirit of scope of the invention. For example, the disclosed counter/time could easily be used for other types of sporting events, such as runners running laps or vehicles driving around a predetermined course. Because each unit can operate within a relatively narrow bandwidth, it is also contemplated that multiple swimmers could use multiple device simultaneously in the same pool, provided that each swimmer uses a device and transmitter tuned to a different frequency. Although the preferred embodiment utilizes two spaced receivers and a pulsing signal to monitor a swimmer, the present invention contemplates that a continuous transmitted signal could be used with single receiver with a doppler shift system to monitor the position and direction of the swimmer. It is also contemplated that the display inversion feature of the present invention could be used with virtually any other type of sensor for detecting the person or object being monitored. For example, inversion of the displays could be triggered by a sensor based on a mechanical switch or breaking a light beam. Moreover, many other varieties of visual displays, including those that are mechanically based or alphanumeric dot array LCD's could be used instead of the seven segment LCD displays of the preferred embodiment, as long as the visual display is invertible so as to be easily observable by a swimmer swimming in either direction. It is also contemplated that the interface port terminal could be replaced by recently developed magnetically operated transducers or optically operated transducers to provide an interface port in which the components are completely electrically isolated from the exterior of the housing. Also, the magnetically actuated switches on the device could be easily replaced by optical switches or waterproof "feather-touch" switches.

END OF PL/M-51 COMPILATION

We claim:

1. A sport counting device for monitoring an object moving in repeated laps along a predetermined course, the object continuously transmitting a pulsing signal from a single transmission source comprising:
 first and second receivers capable of detecting the pulsing signal, the receivers being spaced from each other,
 comparing means for determining the time differential between the times the pulsing signal reaches the first and second receivers,
 counter means comprising a visual display,
 counter update means operatively connected to the comparing means such that the counter is updated when the comparing means determines completion of a lap based upon the time differential between the times the pulsing signal reaches the first and second receivers.
2. The sport counting device of claim 1 wherein the counter update means is updated when the time differentials between receipt of the pulses by the two receivers change from increasing to decreasing.
3. The sport counting device of claim 1 wherein the counter update means is updated based on there being substantially no time difference between the times the pulsing signal reaches the first and second receivers.
4. The sport counting device of claim 1 wherein the counter update means is updated based on a change in which receiver receives the signal first.
5. The sport counting device of claim 1 wherein the visual display means displays a lap counter comprising the number of times the counter update means is updated.
6. The sport counting device of claim 1 wherein the visual display means displays the elapsed time between the beginning of a lap and completion of the lap.
7. The sport counting device of claim 1 wherein the sport timer is entirely submersible in water and wherein the visual display is upwardly projecting.
8. The sport counting device of claim 1 further comprising means for displaying the visual display in either noninverted or inverted format, the displaying means being operatively connected to the counter update means.
9. A counting device for an object repeatedly moving in opposite directions past a fixed point comprising:
 sensor means for determining when the object passes by the sensor means,
 timing means,
- 20 visual display means connected to the timing means for displaying a numerical statistic regarding the moving object,
 the visual display means comprising means for displaying the numerical statistic in either non-inverted or inverted format, the display means being operatively connected to the sensor means.
10. The counting device of claim 9 wherein the visual display comprises a seven segment visual display.
11. The counting device of claim 9 wherein the displaying means inverts the visual display based upon the object passing by the sensor.
12. The counting device of claim 11 wherein the inversion occurs a predetermined time after an object passes by the sensor.
13. The counting device of claim 9 wherein the numerical statistic comprises a count of the number of laps completed.
14. The counting device of claim 9 wherein the numerical statistic comprises the time for completion of a lap.
15. The counting device of claim 9 wherein the counting device is submersible in water and wherein the visual display is upwardly projecting.
16. The counting device of claim 9 wherein the sensor means comprises means for receiving a signal transmitted by the moving object.
17. The counting device of claim 16 wherein the receiving means comprises first and second receivers capable of detecting the transmitted signal, the receivers being spaced from each other, and wherein the device further comprises:
 comparing means for determining the time differential between the times the signal reaches the first and second receivers.
18. The counting device of claim 17 wherein the displaying means inverts the visual display based on there being substantially no time difference between the times the pulsing signal reaches the first and second receiver.
19. The counting device of claim 17 wherein the displaying mean inverts the visual display each time the time differentials between receipt of the signal by the two receivers changes from increasing to decreasing.
20. The counting device of claim 16 wherein the means for determining when the object passes by the sensor comprises doppler shift detecting means.

21. A swimming counter for a swimmer swimming laps comprising:
 a waterproof, submersible housing comprising at least one upwardly projecting visual display observable by a downwardly facing swimmer, an internal power source and non-contact detecting means for detecting means for detecting the position of a swimmer relative to the housing, 5

counter means operatively connected to the visual display and detecting means such that the counter means is updated when the non-contact detecting means detects that the swimmer has completed a lap. 10

22. The swimming counter of claim 21 wherein the non-contact detecting means comprises:

first and second receivers capable of detecting a signal, the receivers being spaced from each other, comparing means for determining the time differential between the times the signal reaches the first and second receivers, 15

counter update means operatively connected to the comprising means such that the counter is updated when the comparing means determines completion of a lap based upon the time differential between the times the signal reaches the first and second receivers. 20

23. The swimming counter of claim 22 wherein the counter update means is updated based upon the time differentials between receipt of the pulses by the two receivers change from increasing to decreasing. 30

24. The swimming counter of claim 21 further comprising means for displaying the visual display in either non-inverted or inverted format, the displaying means being operatively connected to the counter update means. 35

25. The swimming counter of claim 21 wherein the visual display displays a count of the number of laps completed.

26. The swimming counter of claim 21 wherein the visual display displays the time for completion of a lap. 40

27. A swimming counter comprising:

a waterproof, submersible housing comprising at least one upwardly projecting visual display and an internal power source, 45

detecting means for detecting completion of a lap, counter means for counting operatively connected to the detecting means,

switch means for starting the counter means, the switch means being actuatable by a magnet passed in close proximity to the housing, 50

data storage means for storing counts of statistics for a plurality of laps,

review switch means for displaying the stored statistics on the visual display, the review switch means being actuatable by a magnet passed in close proximity to the housing. 55

28. The swimming counter of claim 27 further comprising:

an interface port operatively connected to the data storage means such that counts stored in the data storage means may be copied to an external device through the interface port. 60

29. A swimming counter for a swimmer swimming laps comprising:

a submersible, waterproof housing comprising in combination at least one digital visual display, lap completion detection means, 65

counter means operatively connected to the visual display and lap completion detection means such that the counter means is updated when the lap completion detection means indicates that the swimmer has completed a lap,

data storage means operatively connected to the counter means for electronically storing counts generated by the counter means,

a single serial data interface port operatively connected to the data storage means such that counts stored in the data storage means may be copied to an external device through the interface port.

30. The swimming counter of claim 29 further comprising switch means for actuating copying of the counts through the interface port.

31. The swimming counter of claim 30 wherein the switch means is actuatable by a magnet passed in proximity to the switch.

32. The swimming counter of claim 29 further comprising water temperature sensing means attached to the housing, and wherein:

the water temperature may be stored in the data storage means and copied through the interface port.

33. A method for timing a swimmer swimming laps between a starting end and an opposite end, comprising:

providing the swimmer with a transmitter capable of transmitting a signal,

placing first and second receivers capable of receiving the signal between the starting end and the opposite end, the first receiver being closer to the starting end than the second receiver,

providing a time counter,

providing means for storing a first reference count, starting the time counter,

freezing the time counter reading based upon the signal changing from being received first by the first receiver and then by the second received by an increasing time differential, to being so received at a decreasing time differential.

34. The method of claim 33 further comprising:

providing means for storing first, second, third and fourth reference counts,

storing a first reference count when the swimmer begins swimming a lap from the starting end toward the opposite end,

storing a second reference count when the swimmer from the opposite end toward the starting end and the transmitted signal is received by the two receivers substantially simultaneously,

storing a third reference count when the signal changes from being received first by the first receiver and then by the second receiver by an increasing time differential, to being so received with a decreasing time differential,

storing a fourth reference count the next time the swimmer is swimming from the starting end toward the opposite end and the transmitted signal is received by both receivers substantially simultaneously,

computing the difference between the second and fourth reference counts,

updating the frozen time counter reading to be equal to the second reference count plus one-half the difference between the second and fourth reference counts if the third reference count is not within a predetermined percentage of the average of the second and fourth reference counts.

35. The method of claim 34 wherein the predetermined percentage is twenty five percent of the difference between the second and fourth reference counts.
36. The method of claim 33 wherein the time counter begins with a count of from 0.4 to 1.4 seconds.
37. The method of claim 33 further comprising, after

freezing the time counter reading, replacing the reading with a total elapsed time reading based upon the next time the swimmer is swimming from the starting end toward the opposite end and the transmitted signal is received by both receivers substantially simultaneously.
